SPRING DEVICE

William Hagelstein, Arrochar, Staten Island, N. Y.

Application May 9, 1942, Serial No. 442,308

7 Claims. (Cl. 24—255)

This invention relates to improved spring structures.

It is an object of my invention to provide a spring for use with clamps or like fastening devices, imparting thereto, improved holding qualities with minimum use of spring material.

It is an object of my invention to provide a spring adaptable for use with fastening or clamping devices such as clothespins, garment hangers, and the like, and other devices wherein a fastening or clamping member is to be brought into resilient and yieldable engagement with another element.

Spring structures or elements employed with present forms of spring clothespins or garment hangers usually embody a spring having a number of closely positioned coils forming a barrel which is at least the width of the clothespin jaw member; at each end of the coil, an extension of the spring hooks over the respective jaws of the clothespin to complete the assembly. Such spring elements inefficiently employ the spring material; and the jaws of the clothespin or the like are so readily disengaged from the spring member as to render the clothespin vulnerable to failure in service.

A spring structure made according to my invention comprises a relatively short length of spring wire formed with a double spring loop connected by an integral spring link; the power of the spring is the cumulative effect of the resiliency of the loops plus the resiliency of the interconnecting link. For clothespins or the like, two such spring devices are employed, one on each side of the jaws of the clothespin. The free ends of the spring are secured to the jaws, making the same proof against disengagement with respect to the spring.

Other features and advantages will hereinafter appear.

In the accompanying sheet of drawings:

Fig. 1 is a side elevation of a spring clothespin employing my invention;

Fig. 2 is a front elevation of the same;

Fig. 3 is a perspective of a spring constructed according to my invention;

Fig. 4 is a side elevation of a clothespin employing a second form of spring element embodying my invention;

Fig. 5 is a front elevation of the same, partly in section to disclose means of securing the spring to the respective elements of the clothespin;

Fig. 6 shows one application of clothespins embodying my invention; and

Fig. 7 is an elevation of a garment holder or similar clamp, embodying my invention.

Referring first to Fig. 3, a preferred embodiment of my improved spring comprises spaced spring systems 11, 11, desirably interconnected by an integral tie member 12.

Each spring system is formed by bending a spring steel wire to provide angularly related branches 14, 14', at the vertex of which is a loop 15, and at the terminals of which are loops 16, 17. The terminal end of each system extends downwardly and inwardly, as shown.

Each spring system is, in effect, a concatenation of individual spring members, to wit, the loop 15, respective branches 14, 14', and loops 16 and 17.

My improved spring is particularly adaptable to clothespins or like clamping devices, although it is not restricted to such use. As shown in Figs. 1 and 2, a jaw member 20 of a clothespin is passed between the spaced spring systems, the interconnecting member 12 fitting within a slot in said jaw 20, as shown, to confine the jaw against lateral displacement. The coating jaw 21 is positioned between the spring systems, and the inwardly projecting ends thereof are inserted into a passage 22 in said jaw, see Fig. 2.

The spring systems may be secured to jaw 21 by a rivet 23, passed through the jaw and the respective loops 17, and headed over said loops. Preferably the diameter of the rivet should be less than the diameter of the loop, to permit said loop to contract and expand freely when the clothespin is opened. For conventional clothespins, in which the jaws 20, 21 are in engagement when in closed position, and in which one member rocks upon the other when the pin is open, it is not necessary to pass a rivet through the loops 16; the connection 12 completely secures the pin member 20 against displacement. It has been demonstrated that the spring system so adequately holds the jaws 20, 21 against displacement that the clothespin is proof against separation under extreme conditions of use.

I prefer to drill a hole 24, of suitable size to pass a light line or flexible wire, through one of the jaw members, whereby a plurality of clothespins may be permanently strung on a line 25, see Fig. 6. The pins are slidably strung on said line, whereby they may be moved to an end of the line, and the latter wound upon a reel 26.

Fig. 7 shows my improved spring as employed with a towel hanger or the like. Said hanger includes a relatively long jaw member 30, having holes 31, 31 near its ends to permit it to be nailed

to a wall, and a complementary jaw member 32. As shown in Fig. 7, a rivet 33 is passed through loops 16 and the jaw 30. The positive securing of the jaw 30 to the spaced spring systems makes it possible to lengthen the spring arm 14, spacing the members 30, 32 in the zone of the spring, and proportionately increasing the extent to which the members can be spread relative to each other.

In the embodiment of Figs. 4 and 5, the spring systems are structurally independent. The ends of each system extend inwardly into the respective jaws 20, 21, and a rivet 23 is passed through each of the loops 16, 17, to secure the spring systems to the jaws.

The spring actions remain the same, in that each of the loops 15, 16, and 17, spring independently, as do the spring arms 14, 14', when the jaws 20, 21 are rotated about each other in opening the pin.

As in the embodiment of Fig. 7, the arm member 14 may be as long as is desired, to increase the space to which the jaws 20, 21, may be separated and thereby permitting bulky materials to be satisfactorily held between such jaws.

Whereas I have described my invention by reference to specific forms thereof, it will be understood that many changes and modifications may be made provided they do not depart from the scope of the claims.

I claim:

1. An improved spring, comprising individual spring systems maintained in spaced parallel relationship by an integral connection member, each spring system including spring arms in angular relationship one to the other, a spring loop at the juncture of said spring arms, and spring loops at the ends thereof, said spring being formed from a continuous length of spring material.

2. An improved spring, comprising spring arms in angular relationship one with the other, a spring loop at the juncture of said spring arms, and spring loops near the ends thereof, said spring arms terminating in inwardly directed branches.

3. An improved clamping device, comprising a pair of jaw members arranged face to face, and a spring system for maintaining said jaw members in resilient face to face contact, said spring system including spring arms in angular rela-

tionship one with the other, a spring loop at the juncture thereof, and spring loops at the ends thereof, and means for securing said spring system to said jaw members.

4. An improved clamping means, comprising a pair of jaws and spring means for urging said jaws into resilient face to face contact, said spring means including a spring system disposed on each side of said jaws and interconnected with an integral member embracing one of said jaws and cooperating with said spring systems to secure said jaw against displacement, said spring systems comprising angularly related spring members, a spring loop at the juncture of said spring members, a spring loop at each end of said spring members, a rivet passing through a common loop of each spring system and through one of said jaws, and means for securing the free ends of said spring systems to said jaw.

5. An improved clamp, comprising a pair of jaw members and a spring system positioned on each side of said jaw members and secured thereto, said spring system including a pair of angularly related spring arms, a spring loop formed at a juncture of said arms, and a spring loop formed adjacent the end of each of said arms, the terminal ends of said arms projecting into said jaw members, and means for securing said spring systems to said jaw members, including rivets extending through similar loops of said spring systems and through said jaw members.

6. An improved clamp according to claim 5, further characterized by one of said jaw members being longer than the other, and having means for the securement thereof to a supporting surface.

7. An improved clothespin, comprising a pair of jaw members and a spring system positioned on each side of said jaw members and secured thereto, said spring system including a pair of angularly related spring arms, a spring loop formed at a juncture of said arms, and a spring loop formed adjacent the end of each of said arms, the terminal ends of said arms projecting into one of said jaw members, and means for securing said spring systems to said jaw members, one of said jaw members having a passage therethrough to slidably receive a clothesline or the like.
